DESIGN FOR A CAMERA

Freeman H. Owens, New York, N. Y.

Application October 16, 1945, Serial No. 122,901

Term of patent 14 years

(Cl. D61—1)

To all whom it may concern:

Be it known that I, Freeman H. Owens, a citizen of the United States, residing in the city, county, and State of New York, have invented a new, original, and ornamental Design for a Camera, of which the following is a specification, reference being had to the accompanying drawing which forms a part thereof.

Figure 1 is a front elevational view of the camera illustrating my novel design. For convenience of illustration the carrying cord is shown as fragmentary.

Figure 2 is a perspective view of the camera shown in Figure 1 taken from a point to the rear and above the camera, the opposite side elevation of the camera not seen in this figure having the same appearance as the side which is fully shown.

Figure 3 is a top plan view of the camera of Figures 1 and 2.

I claim:

The ornamental design for a camera, substantially as shown and described.

FREEMAN H. OWENS.
